United States Patent Office

Des. 191,155
Patented Aug. 15, 1961

191,155

PEDAL

James Back, Box 532, Riverdale Station, Dayton, Ohio

Filed Aug. 22, 1960, Ser. No. 61,837

Term of patent 14 years

(Cl. D90—14)

FIG. 1

FIG. 2

FIG. 3

FIG. 4

FIG. 1 is a top plan view of a pedal embodying my new design, the bottom being the same as the top shown;

FIG. 2 is a view in elevation of one side thereof, the opposite side being the same as the side shown;

FIG. 3 is an end elevational view thereof taken from the right of FIG. 1; and

FIG. 4 is an end elevational view thereof taken from the left of FIG. 1.

This application is a continuation-in-part of my copending application D. 58,193, now abandoned.

I claim:

The ornamental design for a pedal, as shown and described.
